DESIGN FOR A ROCKING CHAIR

Francis McKee Kirkpatrick, Muncie, Ind., assignor to Durham Manufacturing Corporation, Muncie, Ind., a corporation of Indiana

Application January 30, 1945, Serial No. 117,673

Term of patent 14 years

(Cl. D15—6)

To all whom it may concern:

Be it known that I, Francis McKee Kirkpatrick, a citizen of the United States and resident of Muncie, in the county of Delaware and State of Indiana, have invented a new, original, and ornamental Design for Rocking Chair, of which the following is a specification, reference being had to the accompanying drawing forming a part thereof, in which the single drawing figure is a perspective view of a rocking chair showing my new design.

I claim:

The ornamental design for a rocking chair, as shown.

FRANCIS MCKEE KIRKPATRICK.
